PORTABLE X-RAY STAND OR THE LIKE

Jay Lawrence Tanenbaum, 84 Bayard Ave., North Haven,
Conn. 06473, and Gerald L. St. Marie, 181 Long Lots
Road, Westport, Conn. 06880

Filed Apr. 7, 1966, Ser. No. 1,310

Term of patent 14 years

(Cl. D83—1)

FIG. 1 is a perspective view of a portable X-ray stand or the like, in a fully assembled operative position;

FIG. 2 is a perspective view thereof, in a disassembled partially folded condition;

FIG. 3 is an end elevation of the stand in a fully folded position; and

FIG. 4 is a perspective view thereof.

The broken lines representing the X-ray head member in FIG. 1 is shown for illustrative purposes only.

We claim:

The ornamental design for a portable X-ray stand or the like, substantially as shown and described.
